[57] ABSTRACT

A window guard made up of a plurality of separate panels and including top and bottom tracks to support them, the panels being positionable in a first, edge-to-edge extended position and in that position extending over a large area and covering the window to be guarded, and also positionable in a second position at one end of the area in which they are stacked transverse to their planes, and exposing the window, the tracks having enlarged trays at that end to receive the stack.

WINDOW GUARD

BACKGROUND:

The invention resides in the field of guards for covering windows. Heretofore such guards customarily were movable and removable bodily as complete units, i.e., at night they were put in position over the window, and in the morning they were bodily removed from that position and stored in another position, usually remote from their guarding position. Then when they were to be again placed in position over the window, they were bodily removed from their storing position and replaced in position over the window.

In the use of such guards, the operation of putting them up into position, and removing them therefrom and placing them in a storage position, and again taken from a storage position and placed in position over the window, resulted in great consumption of time, and great physical efforts.

OBJECTS OF THE INVENTION:

A broad object of the invention is to provide a novel window guard construction in the use of which the disadvantages referred to above are overcome.

Another and broad object of the invention is to provide a window guard of novel construction made up of a plurality of panels which when in extended position form a rigid and effectively unitary guard covering the window, and wherein the panels are separate and detachable from each other and are movable individually to a stacked position at one side of the large area which includes the window.

A further object is to provide a construction of the character just referred to which includes a pair of tracks supporting the panels, arranged above and below the area to be covered, and in which the panels are supported both in extended position and in retracted and stacked position at one side of the area, the tracks having an enlarged portion for receiving the panels when in retracted position.

A still further object is to provide in a window guard construction of the foregoing character, novel supporting means operative for retaining the separate panels together in rigid relation when in extended position, and in compact relation when in stacked position, and means for releaseably securing or locking the panels in each of their said positions.

DESCRIPTION OF A PREFERRED EMBODIMENT:

In the drawings:

FIG. 1 is a perspective view of a window guard of the invention arranged in extended position over the window to be guarded;

FIG. 2 is a face view of the guard in extended position as represented in FIG. 1, and taken from the lower right of the latter figure;

FIG. 3 is a perspective view of the lower portion of the window guard as oriented in FIG. 1, showing the panels semi-diagrammatically and indicating the manner of moving them from extended position to stacked position;

FIG. 4 is a view similar to FIG. 1 but with the panels in stacked position, exposing the window;

FIG. 5 is a face view of the device as represented in FIG. 4, being taken from the lower right of the latter figure;

FIG. 6 is a horizontal sectional view taken at line 5 6-6 of FIG. 2;

FIG. 7 is a horizontal sectional view taken at line 7-7 of FIG. 2;

FIG. 8 is a horizontal sectional view taken at line 8-8 of FIG. 5;

FIG. 9 is a horizontal sectional view taken at line 9-9 of FIG. 5;

FIG. 10 is a vertical sectional view taken at line 10-10 of FIG. 2;

FIG. 11 is a vertical sectional view taken at line 11-11 of FIG. 5;

FIG. 12 is a large scale detail view of the portion of FIG. 2 encircled in dot-dash lines and indicated at 12;

FIG. 13 is a view taken at line 13-13 of FIG. 12; and

FIG. 14 is a face view of a modified form of guard structure.

Referring in detail to the accompanying drawings, attention is directed first to FIGS. 1-5. The window guard construction is indicated in its entirety at 20 and includes a guard proper 22 made up of a plurality of panels or sections of any suitable number, in this case four, individually identified 22a, 22b, 22c, 22d. The construction also includes a pair of tracks 24 at opposite sides of the window to be guarded, including an upper track 24u and a lower track 24l. These tracks are in the form of channels having their open sides facing each other and of suitable construction, each including a long narrow portion 26 having an end element 27 and a short wide portion or tray 28 at one end having an end element 29. The long narrow portions 26 extend across the window to be guarded, and preferably slightly therebeyond on both ends, while the tray 28 is of considerably shorter length, but of greater width, and dimensioned for accommodating the panels when in stacked position.

The panels 22 in themselves may be of conventional kind, preferably rigid and each including a surrounding rigid frame member 30 and a filler member 32 preferably in the form of a mesh or screen, such as expanded metal, but which also may be of any character such as a solid imperforate member.

The tracks 24 are mounted on the wall indicated diagrammatically at 34 in which the window 36 to be guarded is located, and although the tracks are preferably positioned above and below the window, the invention is of sufficiently broad scope that they may be disposed vertically at opposite sides of the window.

The panels are of a length to at least cover the window to be guarded and of any additional length as may be desired, and the tracks are spaced apart sufficiently to hold the panels therein without enabling their removal from the tracks when so mounted. The panels are of a width such that when they are in a common plane in edge-to-edge relation in the long narrow portions of the tracks, they cover the window to be guarded (FIG. 2). The long narrow portions also are preferably of such width as to snugly receive the panels so as to prevent undue play in transverse directions.

Certain of the panels, i.e., all but the first or leading panel, are preferably provided with holding clips or cleats 38 (FIGS. 2, 12, 13) welded on opposite sides of

the leading edge thereof and extending forwardly beyond that edge. When the panels are placed in edge-to-edge position as in FIG. 2, the cleats engage the panel before it to aid in solidifying the panels into an effectively unitary and single guard over the window.

The trays 28 of the tracks are of sufficient width to receive all of the panels in stacked position transverse to their planes parallel to the common plane they assume when extended. FIG. 3 indicates diagrammatically the removal of the panels from extended position into stacked position, i.e., the first panel 22a is removed from the narrow long portion 26 of the tracks and slid in retracting direction, to the left in FIGS. 1 and 2, and then moved outwardly away from the surface of the building to the outer edge of the trays 28; then the next panel 22b is slid along the tracks into the trays and moved outwardly and fitted against the first panel and then the next panels 22c and 22d are moved in a similar matter, and when all are moved into the wide portions, they are completely removed from the window 36 to be guarded.

Suitable means may be utilized for retaining the panels in either extended or stacked position, such as padlock connected between the end panel and one of the tracks. Alternatively, a bar 40 (FIG. 1) may be mounted as by hinging at 42 at the back edge of the track and swingable into a position extending across the open side thereof and when in that position engaging a clip 44 mounted on the front edge of the track, and secured thereto by suitable means such as a lock 46. When the bar 40 is secured in the position shown in FIG. 1 when the panels are in extended position, the panels are butted against the end elements 27 of the long narrow portions 26 and the bar prevents removal from that position. When it is desired to move the panels into stacked position, the bar is removed from its locked position of FIGS. 1 and 7, thrown upwardly out of blocking position and then the panels are moved to stacked position as in FIGS. 4 and 5 where they are butted against the other end element 29; the bar again is swung down into blocking position as in FIGS. 4 and 9 and locked, where it locks the panels in stacked position and prevents their removal therefrom.

The dimensions of the tracks and panels are such that the panels cannot be removed from the tracks in an unauthorized manner, i.e., so long as the tracks are mounted in proper position, since the panels cannot be tilted in either direction from their confined upright position.

A great advantage of the invention is that the panels, or guard proper, can be put into guarding position and removed therefrom in a very simple manner, with a minimum of time and effort. The panels may be of conveniently small size for easy manual manipulation, i.e., they can be slid along the tracks with a minimum of effort both to extended position and to stacked position. It is not necessary to bodily remove the guard when it is desired to expose the window, to another and remote storage position, which has heretofore usually been necessary, since upon removing the guard from guarding position it was impractical, if not impossible, to retain the guard near the window which was guarded. The panels can be made of such small size that when they are removed from the window and put in stacked position, they occupy an extremely small space relative to the total area being guarded.

The foregoing referred to use of the device for guarding a window, but it is also practical to utilize it for guarding a door and in that case the lower track 24l would be disposed across the treadway of the doorway.

- 5 In that case the lower track may be jack-knifed as represented in FIG. 14, which for that purpose includes a fixed wide portion 48 and a narrow long portion 50 hingedly mounted on the wide portion at 52 so that it can be swung up out of position interfering with the 10 treadway of the doorway. FIG. 14 shows the long narrow portion in upper position where it may be detachably secured by suitable means indicated at 54 such as a device mounted on the upper track or on the wall or any fixed element. While a jack-knifing construction in 15 itself is old, in the present instance it provides a convenient manner of securing the panels 22 in stacked position, while clearing the treadway of the doorway.

I claim:

- 20 1. A guard construction for covering an area, comprising,

a pair of tracks, straight throughout their length, at the upper and lower edges of the area, the tracks being channelshape with concave sides interfacing, the tracks being congruent in vertical projection and each having a narrow section extending the horizontal extent of the area and a wide section communicating therewith positioned horizontally beyond the area,

a plurality of panels together forming a guard slidably mounted in the tracks against removal therefrom and supported by the tracks, the panels being of a thickness similar to the width of the narrow portions of the tracks and confined thereby against transverse displacement,

the panels also being detached from each other and individually movable in the tracks, and of such width that when placed contiguously in edge-to-edge position they extend, together, across the area and substantially the full longitudinal extent of the narrow sections of the tracks,

the width of the panels further being similar to the longitudinal extent of the wide sections of the tracks,

the panels being slidable between their edge-to-edge position in the narrow sections of the tracks and their position in the wide sections thereof in which they are fitted flat together in face-to-face engagement, the width of the wide sections being similar to the corresponding thickness of the stack of panels and the wide sections confining the panels against transverse displacement, and

means at the juncture of the narrow and wide sections of the tracks for releaseably locking the panels respectively in the narrow sections and in the wide sections, selectively.

- 55 2. A guard construction according to claim 1 wherein all of the panels except the leading panel remote from the wide sections of the tracks have cleats at one edge on opposite faces engageable with corresponding faces of the panel next ahead thereof, whereby to provide a rigid and effectively continuous guard member covering the area, confined by the cleats against displacement out of a common plane in which all of the panels are disposed.

- 60 3. A guard construction according to claim 1 adapted for covering an area forming a doorway and in which

the lower track is disposed adjacent the treadway through the doorway, wherein

in the case of the lower track, the wide section thereof is mounted on the structure having the area to be covered by the guard and the narrow section thereof is pivotally mounted on the wide section and otherwise free of connection of the structure,

the narrow section of the lower track being swingable between a lower position in which it is on the treadway and an upper position in which it is disposed vertically and engages or approaches the upper track,

means for releaseably locking the swingable end of the narrow section of the lower track, when in vertical position,

the narrow swingable section of the lower track being operative for engaging the final panel in the stack of panels in the wide sections of the tracks when that narrow section is moved up into upper position, and directly confining that panel in the wide sections and thereby confining all of the panels therein against removal therefrom into the narrow sections.
